UNITED STATES PATENT OFFICE

DAVIS B. REYNOLDS, OF NEW YORK, N. Y., ASSIGNOR TO DANIEL FOBES,
OF CAMBRIDGE, AND LYCURGUS BURNHAM, OF WOBURN, MASS.

IMPROVEMENT IN STOOLS.

Specification forming part of Letters Patent No. **215,773**, dated May 27, 1879; application filed
June 28, 1878.

To all whom it may concern:

Be it known that I, DAVIS B. REYNOLDS, of New York city, State of New York, have invented a new and useful Attachment for Camp-Stools; and I hereby declare that the following specification and the accompanying drawings give a correct description of the same.

My invention relates to folding or detachable camp-stools of the tripod form; the object of the same being to prevent the legs of the stool from spreading apart and breaking from the weight of the person resting thereon.

The nature of my invention consists in connecting the feet of the tripod-stool to each other in a peculiar manner to be described.

Figure 1 is a perspective view of the device seen as applied to the feet of a tripod. Fig. 2 is a similar view of the device seen by itself, and Fig. 3 shows the manner of folding it into small compass for convenience of carrying.

Referring first to Fig. 1, each foot of the stool is furnished with an adjustable thimble, A, fitting over the same. To each thimble is fastened a strap or band, B, (made preferably of thin elastic metal,) extending inward to the

center of the circle on the circumference of which stand the feet of the stool. The ends of the bands thus brought together are placed one above the other, and fastened loosely together by a single rivet, C.

When the apparatus is to be taken apart, the thimbles A are first slipped off the feet, and then the three bands B are folded together as closely as possible, so as to be easily carried. I prefer to make the three thimbles A of graduated sizes, so as to fit into each other, as in Fig. 3; but this is not essential.

Instead of the flat bands B described, wires or cords suitably attached might be used.

I claim—

As an attachment for a tripod camp-stool, the combination of the three thimbles A A A and the three bands B B B, the whole being arranged and connected substantially as described, and for the purposes explained.

DAVIS B. REYNOLDS.
